RESETTING MECHANISM FOR WEFT
REPLENISHING LOOMS

Victor H. Jennings, Worcester, Mass., assignor to
Crompton & Knowles Loom Works, Worcester,
Mass., a corporation of Massachusetts

Original application July 29, 1942, Serial No.
452,738, now Patent No. 2,326,863, dated August
17, 1943. Divided and this application May 8,
1943, Serial No. 486,240

6 Claims. (Cl. 139—264)

This is a division of my co-pending application Serial No. 452,738, filed July 29, 1942, and issuing as Patent No. 2,326,863, dated August 17, 1943.

This invention relates to improvements in thread cutters and clamps for weft replenishing looms and it is the general object of the invention to construct the thread cutter in such a way that it will have a sufficiently long range of motion to insure cutting by the temple cutter soon after a replenishing operation.

In weft replenishing looms it is customary to sever the thread of the outgoing bobbin by a thread cutter which is moved rearwardly from its normal inactive forward position incident to a transferring operation, and during rearward motion the cutter blade is swung to open position by a link hung eccentrically with respect to the center around which the thread cutter swings. As heretofore constructed such thread cutters have had a limited range of movement due to the construction of the link or rod which operates the movable cutter jaw. As a result of this small range of movement the thread is not moved forwardly a sufficient distance to permit cutting by the temple cutter until several picks have elapsed after transfer and there is danger that if transfers occur on successive arrivals of a shuttle under the magazine the thread clamp will release the thread of the first transfer before it has been cut at the temple.

It is an important object of my present invention to provide a control for the rod which operates the movable cutter blade in such a manner as to permit the cutter and clamp to move forwardly a sufficient distance to draw the clamped thread into the temple cutter on a transferring pick of the loom, thus insuring cutting of the thread at the selvage before a second transfer can occur.

It is another object of my present invention to provide a lost motion connection between the movable cutter and clamp operating rod and its support so constructed that the cutting will be effected on the first part of the forward cutting stroke of the cutter, after which the lost motion connection operates to permit a considerable forward motion for the purpose of moving the thread into the temple cutter. This same lost motion connection is also effective to release a previously clamped thread early in the rearward motion of the cutter before it moves over the lay. The thread is therefore able to fall in front of the lay without danger of being entangled with the shuttle and being drawn into the warp shed.

It is a further object of my present invention to provide the operating rod for the movable cutter with resilient means which prevents accidental opening of the clamp when the cutter is in inoperative position.

It is a more specific object of my present invention to provide a pivoted cutter carrier having a movable cutter blade thereon connected by a rod to a support eccentric with respect to the axis of the carrier and wherein the rod is provided with a pair of spaced grooves to receive a yielding lock effective to operate the cutter at two different points in the stroke of the carrier. The first point occurs early in the backward stroke to release a clamped thread, and the second point occurs early in the forward stroke to cut the thread of the outgoing bobbin.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of a portion of a weft replenishing mechanism viewed from the center of the loom and having my invention applied thereto,

Fig. 2 is an enlarged view of a portion of Fig. 1 showing the cutting mechanism in two different positions near the forward limit of its stroke,

Fig. 3 is a view similar to Fig. 2 but showing the cutter mechanism in two other positions near the rearward limit of its stroke,

Fig. 4 is a detail vertical section on line 4—4 of Fig. 2,

Fig. 5 is a diagrammatic plan showing the relation between my improved thread cutter, the fabric being woven, the temple cutter and the lay,

Fig. 6 is a view similar to Fig. 4 but with the parts in different position corresponding to Fig. 3,

Fig. 7 is a view similar to a part of the lower end of Fig. 3 but with parts removed to illustrate the movable cutter and the stops with which it cooperates,

Fig. 8 is a vertical section on line 8—8 of Fig. 7 and

Fig. 9 is a front elevation looking in the direction of arrow 9, Fig. 1, on an enlarged scale.

Referring to Fig. 1, I have shown a loom frame 10 having a magazine M provided with a transferred arm 11 carrying the usual latch 12 to be positioned for transfer by a rod 13. The lay 15 swings backwardly and forwardly and is provided with a shuttle box 16 to receive a shuttle S. A bunter 17 on the lay cooperates with the latch 12

when the latter is raised on the forward beat of the lay on transferring picks of the loom to effect downward movement of the transerrer arm so that a bobbin B in the magazine can be inserted into the shuttle S. During transfer a thread T extends from the selvage of the fabric F into the shuttle box 16 and is attached to the bobbin in the shuttle. It is this thread, shown in Fig. 5, with which my present invention is concerned.

Secured to the magazine is a stand 20 having a pivot 21 on which is mounted a bell crank lever 22 one arm of which is connected to an upwardly extending link 23. The depending arm of lever 22 carries a pivot pin 25 on which is mounted a carrier 26 having a stop 27 held against a second stop 28 on the bell crank lever by a compression spring 29. The forward or right end of this spring, as viewed in Fig. 3, engages an upwardly extending horn 30 on the carrier 26, while its rear end extends into a pocket in lever 22 to engage the latter. The purpose of spring 29 is to permit forward yielding of the carrier with respect to the bell crank lever to avoid breakage.

The lower end of the carrier is provided with a rearwardly and horizontally extending foot 35 to which is secured a stationary cutter blade 36 and on which is pivoted the movable blade 37. The latter swings about a stud 40 secured to the foot 35 and on which is slidably mounted a clamp plate 41, the rear end of which is guided by a pin 42 extending laterally from the foot 35. The blade 37 moves between the stationary blade 36 and the clamp 41 and the latter may be held tightly against the movable blade by a spring 43 secured to the carrier 26.

The swinging cutter has a forwardly extending finger 45 pivoted as at 46 to a rod head 47 adjustable on the lower end of an operating rod 48. The upper end of the rod is guided by a rocking bearing 50 pivoted to the support 20 as at 51. The bearing 50 is free to swing on its axis 51 as the angle of the operating rod changes and the rod is free to slide longitudinally through the bearing.

The loom frame 10 is provided with a temple 55 which extends along the right selvage of the fabric to a point spaced a slight distance in advance of the fell 56 of the cloth. The thread T extends from the intersection of the fell and selvage into the shuttle box, but is ordinarily behind the range of action of the temple cutter 57, since the latter is set several picks in advance of the fell of the cloth. The lay operates the temple cutter on each forward beat in the usual manner.

The cutter and clamp unit is positioned as to its extreme front and rear positions by the mechanism shown in Fig. 9. The link 23 is connected at its upper end to an arm 80 secured to a rock shaft 81 journaled on the magazine M. A second arm 82 fixed to shaft 81 has swivelled thereon a block 83 slidable in the slotted arm 84 pivoted at 85 to the magazine. A spring 86 in slotted arm 84 bears against the block and tends to hold arms 82 and 84 yieldingly in either of two positions. A lug 87 on the magazine cooperates with stop screws 88 and 89 on arm 84 to position the latter, and therefore arm 82, on either side of a line joining centers 81 and 85. These parts constitute a yielding lock L to hold shaft 81 in its normal and transfer positions. By well known mechanism shaft 81 is turned clockwise as seen in Fig. 9 when a replenishing operation is called to move screw 89 away from and screw 88 against lug 87.

The matter thus far described, except as indi-

cated hereinafter, may be of usual construction and reference may be had to prior Patents Nos. 1,030,748 and 1,633,648 for a further description of the manner in which the combined cutter and clamp is constructed, mounted and connected to operating parts of the magazine. It is thought sufficient for present purposes to state that the carrier 26 is normally in the extreme forward position as shown in Fig. 1 due to the fact that link 10 23 is down, but when a replenishing operation of the loom is called rod 23 is raised to swing the carrier around its pivot 21 toward rearward cutting position. Thereafter the carrier is returned to its normal forward inoperative position by downward motion of the rod 23 by mechanism to be described. During this operation the cutter moves through a much wider angle than has been possible heretofore.

In carrying my present invention into effect 20 I provide means by which the carrier can be moved forwardly far enough to draw the thread T into the temple cutter 57. To accomplish this result I provide the operating rod 48 with two vertically spaced peripheral grooves 60 and 61 for reception of a ball lock 62 slidably mounted in an extension 63 of the rocking bearing 50. A light compression spring 64 within the extension 63 bears against the ball to force the latter against the rod and into the grooves and the pressure exerted by spring 64 may be varied by adjustment of screw 65 threaded into the end of the extension 63. A collar 67 is adjustably held on the rod 48 by a set screw 68 and supports the lower end of a compression spring 69 surrounding the rod 48 and positioned for engagement 30 with the lower end of the bearing 50. Screw 38 holds a stop plate 39 over and in the path of blade 37 and foot 35 is provided with a second stop 72 for the movable cutter blade 37 which may conveniently take the form of a screw lying above the arm 45 and assisting in holding the stationary blade 36 to the foot 35, as shown in Fig. 7.

As already stated the carrier for the combined 40 cutter and clamp has a much larger motion than similar mechanisms heretofore used. It has been former practice to rely upon engagement of the advancing lay with the foot 35 to move the carrier 26 forwardly sufficiently to permit the resetting mechanism at the top of the magazine to complete forward motion of the carrier. In the present instance, however, the lay would give the carrier insufficient motion for its resetting and for that reason I employ the connections 50 shown in Fig. 9.

I provide the hub 90 of the transerrer arm lever 11 with a small arm 91 which is pivoted as at 92 to the lower end of a link 93. The upper end of link 93 is slotted at 94 to receive a stud 60 95 on an arm 96 secured to shaft 81. Arm 96 is extended beyond stud 95 to have connection at 97 with the upper end of previously described transerrer latch controlling rod 13. The usual lost motion connection 98 is provided between rod 13 and the latch 12, see Fig. 1.

In operation the parts will normally be in the position shown in full lines in Figs. 1, 2 and 9 with arm 80 down, arm 96 up and stud 95 located a considerable distance above the bottom of slot 70 94. Rod 13 will also be up so that the transerrer latch 12 can be in its down non-working position as shown in Fig. 1, and the cutter and clamp unit will be in position I, Fig. 5. When a replenishing operation is called by the weft detector mechanism 75 not shown the magazine will be set for transfer,

and shaft 81 will be rocked in a clockwise direction, Fig. 9, to lower arm 96 so that latch 12 will rise to working position and stud 95 will move to the bottom of slot 94. Link 23 is also raised to swing carrier 26 to its rearmost position, see full lines Fig. 3 and position III, Fig. 5. Under these conditions the transferrer arm is still raised so that arm 91 is down with link 93 in its low position.

At the start of rearward movement of carrier 26 the ball 62 will be in groove 61 as shown in Fig. 4 and because of the difference between the centers 21 and 51, the cutter blade 37 will move against stop 72 as shown in Fig. 7 and down to open position to release a previously clamped thread. This release will occur when the parts are in the position of II, Fig. 5, and dotted line position of Fig. 2, shortly after rearward movement of the carrier 26 has started. With blade 37 against stop 72 further rearward movement of the carrier 36 will cause rod 48 to slide down through the bearing 50, ball 62 moving out of groove 61, along that part of the rod between grooves 60 and 61, and into groove 60 to the position of Fig. 6 which corresponds to the full line position of Fig. 3. It is thus apparent that the clamp releases a thread early in the backward movement of the carrier, and in fact considerably before the carrier has completed the first half of its rearward movement. The thread thus released falls in front of the lay. When the carrier has moved to its rearmost position the thread T will enter the bight between blades 36 and 37 due to forward movement of the lay.

As the lay continues to advance its bunter 17 will engage the latch 12 to rock the transferrer arm 11 counter-clockwise as viewed in Fig. 1 and cause upward movement of arm 91 and link 93. Inasmuch as stud 95 is at the bottom of slot 94 at this time, upward movement of rod 93 will immediately start to rock lever 96 which in turn will rock shaft 81 counter-clockwise, see Fig. 9, to lower link 23 and start the carrier 26 on its return or forward movement. During descent of the transferrer arm 11 rod 93 by its upward movement raises lever 96 and rocks shaft 81 until the lock L passes its center, after which the lock completes movement of the shaft 81 and parts connected to it to normal or reset position. The increased motion of the cutter and clamp unit is so large that the lay by its engagement with foot 35 could not of itself move the lock up to or past its mid position, and it is in order to secure sufficient movement of the lock to insure resetting that I employ the transferrer operated rod 93.

Since the ball 62 is in the groove 60 at this time, the jaw 37 will start to close immediately upon the beginning of forward movement of carrier 26 and when the latter has moved from the full to the dotted line position of Fig. 3, corresponding to position IV, Fig. 5, blade 37 will have cut and clamped thread T and will have moved against stop 39. That part of thread T between blade 36 and the shuttle S will be free to follow the outgoing bobbin and that part of the thread between blade 36 and the selvage will be clamped between parts 37 and 41. Forward movement of the carrier 26 occurring thereafter will cause the rod 48 to slide upwardly through the bearing 50, unseating the ball from groove 60 and rolling it along rod 48 to groove 61 which it enters when the forward movement of carrier 26 is completed. A light spring 69 between bearing 50 and collar 68 on rod 48 holds the cutter 37 in closed position

and prevents opening of the clamp under loom vibration.

Thus it is seen that the thread T is cut early in the forward movement of the carrier at a time before the latter completes the first half of its forward movement, and the clamped end of the thread is moved far enough forward to draw that end of it next to the selvage into the range of action of the temple cutter 57. The parts 10 then remain in their reset position until the next replenishing operation is called, and the temple cutter 57 will be able to sever the clamped thread T shortly after the replenishing operation and preferably before the next replenishing operation.

15 After thread T has entered the bight between the cutters the carrier 26 reaches the position IV, Fig. 5 before advance movement of the lay can slacken the thread T sufficiently to permit it to fall out of the cutters. During this cutting operation there may be a slight relative movement of the thread rearwardly with respect to the forwardly moving jaw 37, but the latter will operate to cut thread T before moving far enough forwardly to get away from the thread.

20 25 From the foregoing it will be seen that I have provided a simple mechanism for controlling a thread cutter and clamp unit to permit release of a thread early in the movement of the cutter from normal to working position, after which the 30 yielding lock permits completed movement of the unit toward rearmost position. It will further be seen that the yielding lock operates to effect thread cutting early in the forward motion of the cutter when the released thread can be 35 drawn out of the shuttle by the descending depleted bobbin, after which the lock yields to permit forward movement of the cutter to normal position for locating the clamped thread in the range of operation of the temple cutter. It will further be seen that the movable blade 37 operates between two stops which cooperate with the 40 yielding lock 62 to operate the cutter and clamp unit early in its opening and closing strokes. It will also be seen that the spring 69 serves to hold 45 the blade 37 in closed clamping position when the cutter is in extreme forward position as shown in full lines in Fig. 2. It will further be seen that the rod head 47 permits an adjustment 50 between the cutter blade 37 and the yielding lock.

Having thus described my invention it will be seen that changes and modifications may be made therein by those skilled in the art without departing from the spirit and scope of the invention and I do not wish to be limited to the details herein disclosed, but what I claim is:

1. In thread control mechanism for a loom having a lay to operate the latch of a trans- 60 ferrer arm and having also a shaft which rocks from normal to transfer position preparatory to a replenishing operation of the loom, a combined thread cutter and clamp unit connected to the shaft to be moved from normal to thread receiving position when the shaft moves to trans- 65 fer position and move back to normal position when the shaft returns to normal position, a lever secured to the shaft and moving with the latter from normal to transfer position, means connecting the lever to the transferrer latch pro- 70 viding a lost motion connection to move the latch to position for operation by the lay when the shaft turns to transfer position and permitting movement of the lever to normal position while the latch is engaged with the lay, and 75 other means connected to the transferrer arm

and the lever providing a lost motion connection between the transerrer arm and the lever so constructed as to permit movement of the lever to transfer position independently of movement of the transerrer arm but requiring the lever to move from transfer to normal position when the transerrer arm is operated by the lay.

2. In thread control mechanism for a loom having a lay to operate the latch of a transerrer arm and having also a shaft which rocks from normal to transfer position preparatory to a replenishing operation of the loom, a combined thread cutter and clamp unit connected to the shaft to be moved from normal to thread receiving position when the shaft moves to transfer position and move back to normal position when the shaft returns to normal position, a lever secured to the shaft and moving with the latter from normal to transfer position, a connector including a lost motion mechanism from the lever to the transerrer latch to move the latter into position for operation by the lay when the shaft moves from normal to transfer position, and a second connector from the lever to the transerrer arm including a lost motion mechanism by which the lever is movable to operate the first connector without communicating force to the transerrer arm and by which the latter when moved by engagement of the latch with the lay moves the lever to cause the shaft to return from transfer to normal position and thereby move the cutter and clamp unit from thread receiving to normal position.

3. In thread control mechanism for a loom having a lay to operate the latch of a transerrer arm and having also a shaft which rocks from normal to transfer position preparatory to a replenishing operation of the loom, a combined thread cutter and clamp unit connected to the shaft to be moved from normal to thread receiving position when the shaft moves to transfer position and move back to normal position when the shaft returns to normal position, a lever secured to the shaft and moving with the latter from normal to transfer position, a connection from the lever to the latch to move the latter to position for operation by the lay when said shaft moves from normal to transfer position, a stud in said lever, and a rod connected to the transerrer arm and having a slot to receive the stud, said stud normally located in a position spaced from the end of the slot adjacent the transerrer arm and moving to said end of the slot when the shaft moves from normal to transfer position, subsequent movement of the transerrer arm when the lay engages the latch causing the rod acting through the stud to move the lever and shift the shaft from transfer to normal position and thereby move the cutter and clamp unit from thread receiving to normal position.

4. In thread control mechanism for a loom having a lay to operate the latch member of a transerrer arm member and having also a shaft which rocks from normal to transfer position preparatory to a replenishing operation of the loom, a combined thread cutter and clamp unit connected to the shaft to be moved from normal to thread receiving position when the shaft moves to transfer position and move back to normal position when the shaft returns to

normal position, a lever secured to the shaft and moving therewith from normal to transfer position, a connector between the lever and the latch member, a second connector between the lever and the transerrer arm member, and each connector providing a lost motion mechanism between the member connected thereto and the lever, the first connector acting to move the latch member into position for engagement by the lay when the lever moves from normal to transfer position and the second connector acting to return the lever from transfer to normal position when the transerrer arm member is given a transferring movement by the lay and latch member and cause the shaft to move said unit from thread receiving back to normal position.

5. In a thread control mechanism for a loom having a lay to operate the latch of a transerrer arm and also a shaft with a lever secured thereto which rocks from normal to transfer position preparatory to a replenishing operation and then has a reverse rocking back to normal position, a combined thread cutter and clamp unit connected to the shaft and moved by the latter from normal to transfer thread receiving position when the shaft moves to transfer position and back to normal position when the shaft returns to normal position, a spring lock operative in a given point in the movement of the lever from transfer to normal position to complete said movement, means connecting the lever to the transfer latch providing a lost motion connection to move the latch into position for operation by the lay when the lever moves to transfer position and permitting movement of the lever to normal position while the latch is engaged with the lay, and other means operated by the transerrer arm when the latter has a transferring stroke to move said lever from transfer toward normal position and beyond said point.

6. In a thread control mechanism for a loom having a lay to operate the latch of a transerrer arm and also a shaft with a lever secured thereto which rocks from normal to transfer position preparatory to a replenishing operation and then has a reverse rocking back to normal position, a combined thread cutter and clamp unit connected to the shaft and moved by the latter from normal to transfer thread receiving position when the shaft moves to transfer position and back to normal position when the shaft returns to normal position, a spring lock operative in a given point in the movement of the lever from transfer to normal position to complete said movement, means connecting the lever to the transfer latch providing a lost motion connection to move the latch into position for operation by the lay when the lever moves to transfer position and permitting movement of the lever to normal position while the latch is engaged with the lay, and other means providing a lost motion connection between the transerrer arm and said lever so constructed as to permit movement of the lever to transfer position independently of the transerrer arm and operated by the transerrer arm when the latter has a transferring stroke to move said lever from transfer toward normal position and beyond said point.

VICTOR H. JENNINGS.
